UNITED STATES PATENT OFFICE.

JOHN H. BATTEN, OF WICHITA, KANSAS.

RAIL-BRACE.

1,147,671.

Specification of Letters Patent. Patented July 20, 1915.

Application filed May 10, 1915. Serial No. 27,028.

To all whom it may concern:

Be it known that I, JOHN H. BATTEN, a citizen of the United States, and a resident of Wichita, in the county of Sedgwick and State of Kansas, have invented an Improvement in Rail-Braces, of which the following is a specification.

This invention relates to braces, and more particularly to new and useful improvements in rail braces.

An object of the invention is the provision of an improved brace which will effectively prevent spreading or creeping of the rails of a track thus minimizing the danger of derailment of a car or train.

Another object of the invention is to provide a rail brace for accomplishing the above result which comprises a pair of clamping members, one of which is movable laterally and longitudinally relative to the other whereby the brace may be detached from the rail.

A still further object is to provide a brace of the above character which will possess advantages in points of simplicity of construction, durability, efficiency, and one which is inexpensive to manufacture.

The inventive idea involved is capable of receiving a variety of mechanical expressions, one of which, for the purpose of illustrating the invention, is shown in the accompanying drawing, in which—

Figure 1 is a plan view of the rail brace showing the application thereof when in locked position. Figs. 2, 3 and 4 illustrate successive positions in the operation of detaching the brace from the rails. Fig. 5 is a section on the line 5—5 of Fig. 4.

Referring more particularly to the drawing in which like reference characters indicate similar parts, the numeral 6 indicates the rails of a track.

The rail brace which comprises the essential feature of this invention consists of a pair of clamping elements 7 and 8 which extend transversely of the rails 6 and are provided on the ends adjacent said rails with the rail engaging portions 9. When the elements are in locking position the adjacent edges thereof abut and lugs 10 formed on said edges engage corresponding notches 11 in the edge of the opposite element whereby the same are effectively prevented from longitudinal movement relative to each other. The clamping element 7 is provided with short longitudinally extending slots 12

adapted to receive pins 13 carried by the links 14 which are pivoted to clamping element 8 at 15 thus connecting the two elements together.

The clamping element 8 has pivoted at 16 intermediate the ends thereof a bell crank lever 17 which in turn has pivoted thereto at 18 one end of a connecting arm 19 the other end of which has pivoted thereto a guide collar 20 which slides on the element 8 and is adapted to receive the adjacent inner end of the element 7 when the parts are in locking position as shown in Fig. 1. One extremity of the bell crank lever also has pivoted thereto at 21 a connecting arm 22 the other end of which is pivoted to a guide collar 23 similar in construction to the guide collar 20 and which is adapted to slide on the element 7 and receive the inner end of the element 8 when the parts are in locking position thereby preventing lateral movement of the elements relative to each other. Adjacent the inner end of the element 8 the same is provided with a laterally extending arm or bracket 24 having an opening therein adapted to receive a locking bolt 25 which engages an opening formed in the lever 17 whereby the parts are retained in locked position. The element 7 is also provided intermediate its ends with an arcuate slot 26 which is enlarged at one end as indicated at 27, said slot being adapted to receive a pin 28 carried by the lever 17 for a purpose which will appear in the course of this description.

When it is desired to remove the brace, the bolt 25 is first detached which permits of the lever 17 being swung to the position shown in Fig. 2 when the guide collars 20 and 23, through the medium of the connecting arms 19 and 22, will be slid outwardly from engagement with the adjacent inner ends of the opposite elements. When the parts are in this position the element 8 will be free to move laterally relative to the element 7 which movement will be caused by the pin 28 moving to the position shown in Fig. 3 when the pressure of said pin against the wall of the slot will cause the two clamping elements to separate, as shown, and the pins 13 of the links 14 will move to the ends of their respective slots 12. When the elements 7 and 8 are in the position shown in Fig. 3 the lugs 10 will be disengaged from the notches 11 thus permitting relative longitudinal movement be-

tween said clamping elements. Until the pin 28 reaches the position shown in Fig. 3 the fulcrum of the lever 17 will be about the pivot point 18 but as soon as said pin reaches 5 the position mentioned the pressure thereof against the end of the slot will cause the lever 17 to swing about said pin as a pivot and cause the element 8 to move in a longitudinal direction relative to the element 7 10 so that the clamping portion of the said element 8 will be disengaged from the adjacent rail as shown in Fig. 5. This longitudinal movement will cause the pins 13 of the links 14 to move to the other ends of the slots 12. 15 The parts being in position, as shown in Fig. 5, the brace may then be detached from the rails.

I claim:

1. A rail brace comprising a pair of 20 clamping elements having coöperating lugs and notches adapted for engagement with each other when the elements are in locking position, a bell crank lever pivoted to one of said clamping elements, connecting arms 25 pivoted to said bell crank lever, guide collars connected to said arms, each of said collars being slidable on one of said elements and adapted to embrace the inner end of the other element, links connecting said 30 clamping elements, and a pin carried by said bell crank lever and engaging an arcuate slot formed in one of said elements whereby the opposite element is moved laterally and longitudinally relative thereto when the bell 35 crank lever is swung about its pivot.
2. A rail brace comprising a pair of 40 clamping elements having coöperating lugs and notches adapted for engagement with each other when the elements are in locking position, a bell crank lever pivoted to one of said clamping elements, connecting arms 45 pivoted to said bell crank lever, guide collars connected to said arms, each of said collars being slidable on one of said elements and adapted to embrace the inner end of the 50 other element, links connecting said clamp-

ing elements, a pin carried by said bell crank lever and engaging an arcuate slot formed in one of said elements whereby the opposite element is moved laterally and longitudinally relative thereto when the bell crank lever is swung about its pivot, and means 55 for securing said bell crank lever to one of said clamping elements whereby the parts are locked in position.

3. A rail brace comprising clamping elements, and means for initially moving one of said elements laterally relative to the other and then moving the same longitudinally thereof.

4. A rail brace comprising clamping elements, and lever connections for initially moving one of said elements laterally relative to the other and then moving the same longitudinally thereof.

5. A rail brace comprising clamping elements having lugs and notches adapted for interlocking relation when the elements engage the rails of the track, and means for moving one of said elements laterally and 70 longitudinally relative to the other for interlocking the same.

6. A rail brace comprising clamping elements having lugs and notches adapted for interlocking relation when the elements engage the rails of the track, and lever connections for initially moving one of said elements laterally relatively to the other and then moving the same longitudinally thereof.

7. A rail brace comprising a stationary 80 and a movable clamping element, and means for moving said movable element laterally and longitudinally relative to the stationary member.

8. A rail brace comprising a stationary 85 and a movable clamping element, means for moving said movable element laterally and longitudinally relative to the stationary member, and means released by the first-named means for retaining the elements in 90 clamping position.

JOHN H. BATTEN.
